H. J. SCHMITT

WRECK RETRIEVING DEVICE

Filed Sept. 4, 1919

Inventor:
Henry J. Schmitt

By
Joseph Schmitt,
Attorney.

UNITED STATES PATENT OFFICE.

HENRY J. SCHMITT, OF PORTLAND, OREGON.

WRECK-RETRIEVING DEVICE.

Application filed September 4, 1919. Serial No. 321,632.

To all whom it may concern:

Be it known that HENRY J. SCHMITT, a citizen of the United States of America, and resident of Portland, in the county of 5 Multnomah, in the State of Oregon, has invented certain new and useful Improvements in Wreck-Retrievng Devices, of which the following is a specification, reference being had to the accompanying 10 drawing.

My invention relates to marking buoys to be carried on board of a ship so that, in the event of its being wrecked, they may serve to indicate the spot where the wreck 15 lies submerged.

The distinctive object of my invention in to provide means, in connection with marking buoys of the class described, for passing a cable from the buoy to a wreck 20 in such manner as to impart to the latter a sufficient lifting force to draw it to the surface or near enough to the surface to bring it within the convenient application of ordinary salvage methods.

What constitutes my invention will be hereinafter specified in detail and succinctly set forth in the appended claims.

The accompanying drawing presents illustration of my invention that is in the 30 main diagrammatical. Referring thereto,

Figure I is a diagrammatical transverse view of the hull of a floating ship, equipped with my apparatus.

Figure II is a similar view of the ship 35 shown in Figure I submerged with a marking buoy floating upon the surface of the water above it.

Figure III is a view similar to Figure II illustrating the manner in which a lifting cable is, by the aid of the line connection 40 between the submerged hull and the floating buoy applied to the hull for the purpose of lifting it.

Figure IV is a transverse sectional view 45 of the buoy-case in one form of embodiment detached and shown as open, the lid thereof being supported in an open position by an automatically acting rack.

Referring to the numerals on the drawing, 1 indicates the hull of a ship and 2 the deck thereof. Upon the deck is carried medially between opposite sides of the ship a buoy-case 3 into which is passed two stretches of a slidale endless line 5, which 55 may be made of a weight sufficiently light

to enable it to connect the hull 1 with a buoyant member or buoy 6, the floating capacity of the buoy being duly calculated to sustain the weight of the line. The length of the line 5 may be, of course, 60 varied, but, for the purposes of my invention, a length thereof sufficient to stretch between a floating buoy and a hull submerged below it to the depth of say one thousand feet may be employed. The case 65 3 should be of a capacity sufficient for the stowing away within it of all excess length of the line that may be required to be paid out only in case of a wreck.

In service, while the hull is afloat, the 70 line 5 is kept bent, as indicated at 7 and 8, about separated members 9 and 10 that constitute stable portions or connections of the hull itself, the line being passed through apertures 11 and 12 provided for its loose accommodation. In the diagrammatical illustration offered, the members 9 and 10 are represented as side-rails projecting above the deck 2, but it should be understood that such illustration is purely dia-

grammatical, and that the members 9 and 10 represent any preferred separated means for operatively securing the line to the hull. In actual use it would doubtless be desirable to employ special devices for that purpose. 85 Such devices would necessarily be massive and secured to the ship by means of connection having ample strength to meet requirements, and also constructed to facilitate the slipping of the line through apertures corresponding in effect to the apertures 11 and 12. Moreover, in actual service, 90

the stretches 16 and 17 of the line 5, as shown in Figure I, would need to be conveniently stowed away either below the deck 95 2 or in such convenient disposition as would effectively relieve them from constituting obstructions above deck. Such provisions

are matters of detail which may be safely left to the ordinary dictates of good seamanship and with which my invention is at present not concerned. The separation of the members 9 and 10 represents means for spreading apart the stretches 16 and 17 of the line 5, and so preventing entanglement of one of said stretches with the other upon the flotation of the buoy 6 in service.

In Figure II the hull is indicated by the 100 numeral 20 as submerged below the water level 21 and connected by the line 5 with the 105

floating buoy 6 through a ring 22 depending from its bottom. The buoy, as shown therein, having been automatically lifted out of its case 3 by its buoyancy, floats upon the surface 21. In Figure II the line 5 is shown as drawn out to its fullest extent and is displayed in the form of a triangle which is the shape it would assume if it be connected as specified with two separated members 9 and 10. In Figure II, the line 5 is shown as performing only the simple function of a connection between the sunken hull and its marking buoy.

In Figure III the distinctive function of the line 5 is made apparent. As shown in that figure, the line 5 is being utilized as a slideable endless conveyor or leader between the sunken hull and the marker or buoy 6 for a cable feed-line 25 which is assumed to be paid out at its upper end 26 from a source of supply not illustrated, for example, a coil upon the deck of a ship not shown. At 27 the feed-line 25 is, as by a splice or any other convenient means, fastened to the line 5 at any point thereof that may be conveniently reached from above the surface 21. After the connection 27 is effected, the line 25 is, as by manipulation of the line 5, caused to pass downwardly underneath the supporting member or members 9 and 10, as the case may be, say through the apertures 11 and 12, the splice 27 being shown in Figure III as having just passed through the aperture 11. By a continuing haul upon the line 5, the splice 27 is caused to pass with the movement of said line until the feed-line 25 reaches approximately the ring 22 upon the buoy, at which point it is brought within reach of the surface 21 and may be laid hold of by workmen employed in the service. After both ends of the feed-line 25 are, in the manner described, made available for manipulation above the surface 21, its ends 27 may be separated from the line 5, which may thereafter be dispensed with, and the line 25 then slipped through the apertures 11 and 12 independently of the line 5. The feed-line 25 is so designated because it is designed and adapted to be employed as a leader to a cable of any desired thickness which the size of the apertures 11 and 12 may be designed to accommodate. The line 25 may be a light one and may in service be enlarged by successive lengths attached to it until a line of sufficient strength to draw the cable with certainty is arrived at.

When the cable is at last substituted in place of the feed-line 25 it may be utilized in any usual or preferred manner and, by the aid of any usual or preferred mechanism, as a means of lifting the hull 20. As is well known, the weight of a hull in water is comparatively so light as to require but a comparatively small force for lifting it substantially to the surface of the water. When

the hull has been, by means described, lifted close to the surface, it becomes a simple matter to apply ordinary methods in the complete salvaging of it.

The case 3 is shown in the drawing, by way of example, as an oblong box set upon its side and of dimensions adapted to accommodate the buoy 6, whose ring 22 is shown as located upon one side of the buoy. It is obvious, however, that the buoy when afloat may be partially submerged along its greater extent, and that the ring 22, in such case, could be fixed in the end thereof instead of in the side. The case 3, as illustrated, is shown with a hinged lid 28 which is preferably supported upon its hinge when open as by a rack 29 whose teeth engages a supporting member 30 within the case. This detail, as illustrated, shows provision of means for preventing entanglement of the line 5 by the closing of the lid during such time as the line 5 in double lengths is being paid out from the case 3 under the ascending movement of the buoy through the water.

The buoy is preferably provided with guard-rails or fenders 31 for protecting it from injury as by bumping against the side of a salvage boat, for example.

The operation of my device, in view of the foregoing specification, may be briefly described as follows:

One or more independent buoys, as many as may be preferred, are provided, each with its complement of endless line and line connection, for a ship. As long as the ship is afloat, the buoy constitutes only a part of the ordinary ship's furniture and requires no attention other than such inspection from time to time as may be necessary to make sure at all times that it is in proper repair and working order. The instant, however, that the deck 2 is sufficiently submerged below the surface of the water 21 the buoy will be lifted by the water and will draw the line 5 out of the case 3, which is preferably constituted its repository when it is not in actual service. It is obvious that the buoy will perform its function as a marker, irrespective of the endless nature of the line 5, so long as that line is of length sufficient to accommodate itself to the depth of submergence of the hull 20. The only point for consideration, therefore, in determining the length of the line 5 is the maximum depth of the water in which the sinking of a ship is likely to occur.

After a buoy floating above a wreck and connected with it by the means described, is discovered and its location is made sure, the work of salvaging the wreck may be delayed to any convenient season pending preparation for the work.

What I claim is:

1. The combination with the top deck of a ship having transversely disposed open-

ings in the side walls thereof, a buoy casing mounted on said deck intermediate the said side walls, a buoy normally housed in said casing, an endless line slidably connected to the buoy and extending through said openings and below said casing, and means when the ship is submerged below the surface of the water for automatically releasing the buoy from its casing for the purpose specified.

2. The combination with the top deck of a ship having transversely disposed openings in the side walls thereof, a buoy casing mounted on said deck intermediate the said side walls, a buoy normally housed in said casing, an endless line slidably connected to the buoy and extending through said openings and below said casing, a feed line adapted to be connected to said endless line and passed down through the openings in the side walls and up to the opposite side of the ship, and means when the ship is submerged below the surface of the water

for automatically releasing the buoy from its casing for the purpose specified.

3. The combination with the top deck of a ship having transversely disposed openings in the side walls thereof, a buoy casing provided with a pivotal lid mounted on said deck intermediate the said side walls, a buoy normally housed in said casing, an endless line slidably connected to the buoy and extending transversely across the deck through said openings, and means when the ship is submerged below the surface of the water for automatically raising the lid in said casing and permitting the buoy to float to the surface for the purpose specified.

In testimony whereof, I have hereunto set my hand in the presence of two subscribing witnesses.

HENRY J. SCHMITT.
